UNITED STATES PATENT OFFICE.

JOHN T. WEBSTER, OF YONKERS, NEW YORK, ASSIGNOR TO THOMAS POTTER, SON & CO.

DESIGN FOR OIL-CLOTHS.

Specification forming part of Design No. 5,243, dated August 29, 1871.

To all whom it may concern:

Be it known that I, JOHN T. WEBSTER, of Yonkers, in the county of Westchester and State of New York, have invented and produced a new and original Design for an Oil-Cloth; and I do hereby declare the following to be a specification thereof.

The nature of my invention is fully represented in the accompanying photographic illustration, which forms a part of this specification.

What I claim as my invention, and desire to secure by Letters Patent of the United States, is—

The design for an oil-cloth, as shown.
JOHN T. WEBSTER.
